UNITED STATES PATENT OFFICE.

FRANCIS BILLINGHAM, OF NEW YORK, N. Y.

DESIGN FOR LAMP-BRACKET.

Specification forming part of Design No. 7,748, dated September 8, 1874; application filed August 27, 1874.
[Term of Patent 7 years.]

To all whom it may concern:

Be it known that I, FRANCIS BILLINGHAM, of the city, county, and State of New York, have invented and produced a new and original Design for Brackets for Lamps and Lanterns, of which the following is a specification:

The nature of my design is clearly and fully shown in the accompanying photographic impression, to which reference is made; and consists in the employment of a lion's head, A, as a design for the sole support or holdfast of the bracket, into the mouth of which the bracket is secured, and, further, in decorating the bracket with a group of foliage, B, composed of three trefoils, a a a, a cinque-foil, b,

and a bar, c, dotted with umbos or bosses, and also with the two foliated groups C D, as shown.

What I claim as new is—

The design hereinbefore described, and represented in the accompanying drawing, the same consisting of the combination of the lion's head A, and the foliated ornaments B, C, and D, having the configuration described and represented, and applied to the decoration of the bracket in the manner specified and shown.

FRANCIS BILLINGHAM.

In presence of—
E. P. GLEASON,
Wm. H. POST.
